UNITED STATES PATENT OFFICE.

JOHN W. WATSON, OF WAYNE, PENNSYLVANIA.

RECOIL-CHECK.

1,311,629.

Specification of Letters Patent. Patented July 29, 1919.

Application filed December 1, 1915. Serial No. 64,392.

To all whom it may concern:

Be it known that I, JOHN W. WATSON, a citizen of the United States, and a resident of Wayne, county of Delaware, and State of Pennsylvania, have invented certain new and useful Improvements in Recoil-Checks, of which the following is a specification, reference being had to the accompanying drawings.

- 10 My invention relates to recoil or rebound checks for vehicles, and more especially for automobiles and the like, in which it is desirable to control and modify the recoil or rebound caused by the action of the springs 15 by which the frame of the vehicle is suspended upon the axles in assuming their normal position after deflection through the contact of one or more of the wheels of the vehicle with a road obstacle or through other causes. 20 A principal object of my invention is to provide a recoil or rebound check which shall modify and control the recoil or rebound caused by the springs of the vehicle tending to assume their normal position after deflection, but which shall not hinder or retard the compression or deflection of the springs 25 from their normal position due to the contact of one or more of the vehicle wheels with a road obstacle or to other causes; to provide 30 a recoil or rebound check which will not hamper or retard the deflection or compression of the springs during the relative approaching movement of the frame and axle but will become operative to exercise a check- 35 ing and modifying effect during the relative separating movement of the parts, thereby checking the upthrow of the spring-supported portions of the vehicle, and minimizing the danger of breakage of the springs and 40 assisting in keeping the wheels of the vehicle in contact with the road. A further object of my invention is to provide a recoil or rebound check having the foregoing characteristics in which the amount of resistance 45 exerted against the relative separation of the frame and axle of the vehicle may be made substantially invariable, and moreover, may be adjustably controlled if desired.
- Still further objects of my invention are 50 to provide a recoil or rebound check which shall be simple in construction and devoid of intricate and complicated parts; which may be manufactured at a low cost; which is adapted for attachment to practically any 55 type of automobile or other vehicle; which

after once being adjusted in position shall require a minimum amount of care and attention, and which shall not be likely to get out of order in operation or become broken or damaged through rough usage.

My invention further includes all of the other various novel objects and features of construction and arrangement hereinafter more definitely specified and described.

In the accompanying drawing, Figure 1 is a side elevation of a preferred form of the invention as attached adjacent the front axle of an automobile, and Fig. 2 a fragmentary top plan view thereof; Fig. 3 is a side elevation of a similar form of the invention attached adjacent the rear axle of an automobile in a slightly different manner from that shown in Fig. 1, and Fig. 4 a fragmentary top plan view thereof. Fig. 5 is an end elevation of a slightly modified form of the invention as attached adjacent the front axle of an automobile. In Figs. 6 and 7, respectively a top plan view of an automobile chassis and an elevational view thereof taken on line 7-7 in Fig. 6, is shown a slightly different mode of attaching the invention to an automobile or other vehicle, while Figs. 8 and 9 are respectively a top plan view and a side elevation showing details of the device, and Fig. 10 a top plan view showing another detail thereof.

The invention essentially comprises a non-revolving drum adapted to be secured in fixed relation with a portion of an automobile or other vehicle, a cord or band coiled around the drum, one end of the cord being adapted for attachment to another portion of the automobile relatively movable with respect to that portion to which the drum is affixed, and means secured to the other end of the cord operative to, preferably adjustably, tension the same, as hereinafter described.

It will be understood that the invention is adapted to be secured to an automobile or other vehicle which, for example may comprise a frame having side members 1, and front and rear axles 2 and 3 upon which the frame is supported by means of springs 6 and 7 in the usual manner, as will be readily comprehended by those familiar with the art. It will be further understood that the invention is adapted for attachment adjacent each end of one or both axles, although for the sake of clearness in Figs. 1

to 4 inclusive, I have illustrated the invention as applied adjacent only one end of the respective front and rear axles of the vehicle.

5 Referring now more especially to Figs. 1 and 2 that form of the invention therein shown may comprise a drum 10 supported adjacent one of the relatively movable parts of the vehicle, in this case the axle 2, by 10 means of a suitable bracket 12, which may be of any desired or preferred construction, the form of bracket illustrated comprising a portion 13 adapted for engagement between the spring clips 14 of the vehicle, and a 15 flanged inwardly offset portion 16 to which the drum 10 is rigidly secured as by cap screws 18 passing through the flange and into the drum, the bracket being preferably arranged in such manner that the drum will 20 be positioned in substantial alinement with the axle and inside of the frame member 1, with its axis substantially at right angles thereto.

The drum itself may be of any desired 25 construction having either a plain or grooved surface, but may preferably comprise a spiral, substantially semi-circular, groove around its periphery, the width of the groove being preferably slightly greater 30 than the diameter of the cord or band 20 which is coiled around the drum in a longitudinally extending spiral to rest within the groove. One end of the band or cord, which may be of any suitable material, such as a 35 braided cord, and impregnated, if desired, with suitable waterproofing or lubricating material, is secured to a suitable lug or the like 23 fixed with regard to a portion of the vehicle relatively movable to that portion 40 to which the drum is secured, so that in a case where the drum is secured to the axle, as shown in Figs. 1 and 2, an end of the cord may be secured to the frame member 1, preferably substantially vertically above the 45 drum. The other end of the cord after leaving the drum is secured to a suitable spring 25 by means of a clip 26 or other convenient fastening means, which spring is preferably made of considerable length, and secured 50 adjacent its other end to some portion of the vehicle preferably fixed with relation to that portion thereof to which the drum is attached by any suitable means preferably adapted to permit longitudinal adjustment 55 of the spring. For this purpose, and as shown in Figs. 1 and 2, the end of the spring may be secured to an eye-bolt 28 adapted to extend through a suitable support 30 secured to the spring 25 or other convenient part of the vehicle, a pair of lock nuts 32 engaging the end of the eye-bolt protruding through the support serving to secure the eye-bolt in position as well as to 60 permit adjustment of the tension of the 65 spring.

In Figs. 3 and 4 I have illustrated the invention as applied adjacent the rear axle 3 of an automobile, supported on the springs 7 and relatively movable with respect to the frame members 1, but in this case I have 70 illustrated the drum 10 as suitably rigidly secured adjacent the frame instead of the axle as by means of a suitable bracket 35 having a base 36 secured to the frame by bolts 37 and comprising a flange 38 to which the drum is secured by cap screws 39 in a manner similar to that already described in connection with the bracket 12. The bracket 35 is preferably so arranged that the drum will be positioned slightly within the 80 line of the frame and substantially over the rear axle of the vehicle. Instead, however, of attaching one end of the cord 20 to the frame, an end thereof is secured to the axle by means of a suitable clip 40, the cord being thence carried up and around the drum to the spring 25, to which it may be attached by a clip 26, the other end of the spring being connected to the frame or other suitable portion of the vehicle preferably in the 90 manner heretofore described, as by an eye-bolt 28 extending through a fixed lug 30, and adjustably maintained in position by lock nuts 32.

The parts having been constructed and 95 positioned upon the automobile or other vehicle preferably substantially as heretofore described, and the lock nuts 32 preferably so adjusted that when the vehicle is at rest and the frame and axles in their relatively normal position the spring 25 will be under sufficient tension to maintain the cord 20 closely wound about the drum 10, the operation of the invention may be described as follows:—When through the contact of a 105 wheel of the automobile with a road obstacle, or from any other cause, the vehicle springs are flexed and the axle and frame relatively approach each other, the cord will be drawn around the drum by the spring 25 without 110 difficulty, the drum being non-revolving or relatively stationary, the length and adjustment of the spring being preferably such that when the frame and axles have approached each other as closely as the construction of the vehicle will permit, the spring 25 will still be under a certain tension. As soon as the relative approaching movement of the frame and axle ceases the action of the vehicle springs tending to assume their normal position operates to forcibly and rapidly separate the axle and frame, a movement which, if not retarded or modified, results in practice in the sharp upthrow of the spring-supported parts of 120 the vehicle, and sometimes in the breaking of one or more of the vehicle springs as well. This movement of separation between the relatively movable parts of a vehicle equipped with my invention, however, neces- 125 130

sitates the drawing of the cord or band around the drum in a reverse direction from that in which it was drawn around the drum while the relatively movable parts were approaching each other, and owing to the tension exerted on the end of the cord by the spring 25 this movement of the cord in reverse direction can not be accomplished freely, but on the contrary requires a relatively great amount of force owing to the frictional resistance set up between the cord and the drum, the amount of resistance being determined with a drum and cord of given respective diameters by the number of coils of the cord around the drum and the tightness with which they grip the drum as regulated by the tension of the spring 25. Hence it will be seen that while the frame and axle may relatively approach each other with the utmost freedom, as heretofore described, a movement of these parts in the opposite direction may be retarded to any desired degree.

It will furthermore be understood that in practice sufficient adjustment can ordinarily be obtained by means of the adjusting device provided to meet the varied individual requirements of a given class or type of automobile, so that the proportions of the drum and cord and the number of coils of the latter which should be employed for any make or style of vehicle having been determined by the manufacturer of the invention, the individual purchaser thereof after applying the invention to his automobile may by the use of the adjusting means regulate the operation of the device to meet his personal preference, the adjusting means being also utilized when, because of the cord having become stretched in service or from other causes, the initial tension of the spring 25 may have become somewhat lessened.

It will be evident in the forms of the invention heretofore described that as the frame and axle relatively approach during the operation of the device, the tension exerted on the cord by the spring 25 will become gradually less, and that as the frame and axle separate this tension will become gradually greater, and moreover, that each end of the cord will travel a distance equal to that traveled by the other end with respect to the drum presuming the amount of stretch or give in the cord to be substantially negligible. In the form of the invention shown in Fig. 5, however, which illustrates the same as attached adjacent the front axle 2 of a vehicle having frame members 1 supported thereon by vehicle springs 6 in the usual manner although this form of the invention is equally adapted for attachment adjacent the rear axle of a vehicle, the various parts of the device are so arranged that the tension exerted by the spring upon the cord will be constant. Also,

both ends of the cord will travel equal distances with respect to the drum as in the form of the invention already described. In this form of the invention the non-revolving drum 10 is attached to a suitable portion 70 of the vehicle, as, for instance the frame member 1, by means of a bracket 50, which may be substantially similar to the form of bracket shown in Fig. 4, and arranged to maintain the drum a short distance inside 75 of the line of the frame, and one end of the cord 20 attached by a suitable clip 40 to another relatively movable part of the vehicle, as, for instance, the axle 2. One end of the spring 52 is attached to the other end of 80 the cord, after the latter has been coiled around the drum, by means of the clip 53, and the other end of the spring supported by a member 55, the lower end of which is suitably secured to that part of the vehicle, 85 in this case the axle, to which the end of the cord is attached, as by a bracket 56, and the upper end of which is directed in such manner as to bring it into proper relation with the end of the spring 52 to which it may be 90 preferably adjustably secured by any suitable means, as, for example, an eye-bolt 28 and lock nuts 32, as heretofore described, by means of which the tension of the spring 95 may be varied. While I have illustrated a single form of member 55 it will be understood that any other suitable form may be employed, the shape and size thereof being determined primarily by the construction and arrangement of the parts of the vehicle 100 to which the invention is attached. The operation of this form of the invention is substantially similar to the operation of the form heretofore described, except that upon the relative approach of the frame and axle, 105 the member 55 will move with the latter, thereby keeping the spring 52 at constant tension, and that upon the separation of the frame and axle the member 55 will similarly move with the latter, so that no matter what 110 relative position the frame and axle may assume, the tension exerted by the spring upon the cord will always remain constant.

In Figs. 6 and 7 I have illustrated a slightly modified method of attaching the 111 invention to an automobile chassis, said views showing the invention attached adjacent both the front and rear axles thereof. The manner of attaching the invention adjacent the front axle and shown in said figures 12 is substantially similar to that shown in Figs. 1 and 2, the drums 10 being supported adjacent the front axle by suitable brackets 12, a bracket of a form well adapted for this purpose being shown in Figs. 8 and 9, except that instead of separately securing the rear end of each of the springs 25 to springs 6 or other suitable portion of the vehicle, the end of each spring is secured to a cord 60 by means of a clip 61 which cord is carried over 12

a suitable pulley 63 secured to the frame or other suitable member and attached to a suitable turn-buckle 66 or other adjusting means located substantially midway of the 5 sides of the frame by means of which the tension of both springs may be simultaneously regulated. It will be evident that in a construction of this nature tension will be at all times exerted upon both cords 20 10 equally, and that but a single adjustment is required in order to equally regulate the tension of both springs.

A substantially similar manner of installing the invention, as illustrated in Figs. 15 6 and 7, may be employed in connection with the rear axle, a drum being supported on a bracket 70 adjacent each side of the frame preferably substantially in vertical alinement with the rear axle, the cords 20 20 being coiled about their respective drums and secured to the axle as hereinbefore described in connection with Figs. 3 and 4. The other ends of the cords are secured to the springs 25, the ends of which are connected by a suitable cord 73 passing over a pulley 74, in turn secured to a turn-buckle or other adjusting means 75 affixed to a cross-member 76 of the frame or other suitable support, so that by a suitable adjustment of the turn-buckle the tension of the 30 springs may be simultaneously regulated as hereinbefore described. In order that the lead or direction of the springs and adjacent portions of the cord shall be substantially normal to the axes of the respective drums about which the respective cords are coiled, it may be preferable to form the brackets 70 in such manner that each drum shall be maintained with its axis in slightly 35 40 angular relation with the side members of the frame, as clearly shown in Fig. 10. It is believed that the operation of the invention when attached as just described will be evident without detailed description.

45 While I have herein shown and described certain forms of my invention with considerable particularity, and have illustrated them as attached to an automobile or other vehicle in various ways, I desire it to be understood that the invention is equally adapted for use in connection with railway or trolley cars, or in fact with any vehicle or the like having spring-supported parts and in which it is desired to retard or modify the rebound of the springs, and further that the modes of attaching the device which I have shown are merely illustrative and arbitrarily chosen, and that the same may be modified and varied as may be required 50 55 60 in attaching the device to varying makes and kinds of vehicles, and that the invention may be utilized in connection with both the front and rear axles of any given vehicle, or with either of them, and the drums attached either adjacent the axle or adjacent

the frame as may be convenient or desirable. Furthermore, I do not desire or intend to limit myself specifically to the forms of the invention herein illustrated and described, as it will be evident that various 70 changes and modifications may be made in the details thereof and in the form and location of the several parts without departing from the spirit and scope of the invention as defined in the appended claims. 75

Having thus described my invention, I claim and desire to protect by Letters Patent of the United States:

1. A recoil check comprising a non-revolving drum adapted for attachment to a 80 part of a vehicle, a flexible member passing around said drum and having one end adapted for attachment to a part, of the vehicle relatively movable with respect to said first-mentioned part, and means adjacent the other end of said flexible member operative to maintain said flexible member at substantially constant tension. 85

2. The combination with a vehicle having 90 relatively movable parts, of a stationary drum mounted on one of said parts, a flexible member passing about said drum and having an end secured to another of said parts, and means operative to exert substantially constant tension upon the other end of 95 said flexible member.

3. The combination with a vehicle having 100 relatively movable parts, of a recoil check comprising a stationary drum in fixed relation with one of said parts, a flexible member passing around said drum and having an end secured to another of said parts, and a spring adapted to maintain said flexible member under a substantially constant tension during relative movement of said 105 parts.

4. Mechanism for retarding the relative movement between the sprung and unsprung portions of a vehicle in one direction without interfering with their relative movement in the opposite direction, comprising a stationary drum carried by one of said portions, a flexible member coiled around said drum and adapted to be attached at one of its ends to the other of said portions, and means adjacent the other end of said flexible member to maintain said flexible member under substantially constant tension, the relative movement of said vehicle portions operating to cause both ends of said 110 flexible member to move substantially equal distances with respect to said drum. 115

5. The combination with a vehicle having 120 relatively movable parts, of a stationary drum carried by one of said parts, a flexible member passing about said drum and fixed with respect to the other of said parts, and tensioning means so secured to said flexible member and to said last mentioned part as to maintain, substantially constant, 125 130

the frictional resistance offered by the device in one direction.

6. In a recoil check, the combination with relatively movable parts of a vehicle, of a stationary drum supported from one of said parts, a flexible member coiled around said drum and attached at one of its ends to the other of said parts, and tensioning means to which the other end of said flexible member is attached, the mechanism being arranged in such a manner that relative approach and separation of the two first-mentioned parts will cause no material variation in the amount of tension on the last-mentioned end of the flexible member.

7. In a recoil check, the combination with relatively movable parts of a vehicle, of a stationary drum supported from one of said parts, a flexible member coiled around said drum and attached at one of its ends to the other of said parts, tensioning means to which the other end of said flexible mem-

ber is attached, the mechanism being arranged in such a manner that relative approach and separation of the two first-mentioned parts will cause no material variation in the amount of tension on the last-mentioned end of the flexible member and means for adjusting the amount of tension.

8. In mechanism adapted to control relative motion between two elements, a drum adapted to be secured to one of said elements, a friction member in contact with said drum and adapted to be secured to said other element, and means, including a member fixed with relation to said second mentioned element, to maintain, substantially constant, the frictional resistance offered by the device in one direction.

In witness whereof I have hereunto set my hand this 29th day of November, A. D. 1915.

JOHN W. WATSON.
